CARBURETOR

Harold D. Regar, Reading, Pa.

Application April 5, 1941, Serial No. 386,955

2 Claims. (CL. 261—41)

My invention relates to carburetors for supplying combustible mixtures of air and fuel to internal combustion engines, and my object is to provide novel and simply controlled means for insuring proper and economical combustible mixtures for all conditions and requirements of the engine operation.

Generally my carburetor comprises new and improved means for mixing the combustible charges by passing air on its way to the engine over a plurality of fuel nozzles or jets, and progressively increasing or decreasing the number of effective jets, as best suited for varying engine requirements, by means of a determinedly shifted slide valve.

More particularly the nature of my improved carburetor construction and the manner of its effective control for varying combustible mixtures, will be more fully described in connection with the accompanying drawings, and the novel features thereof set forth in the appended claims.

In the drawings:

Fig. 1 is a perspective front elevation of a carburetor embodying my invention, the float valve chamber being omitted, and part of the air inlet conduit broken away to more clearly disclose certain construction features.

Fig. 2 is a front elevation of the carburetor shown in Fig. 1.

Fig. 3 is a sectional plan view, taken on the line 3—3 of Fig. 2.

Fig. 4 is a partial sectional elevation taken on the line 4—4 of Fig. 3.

Figs. 5 and 6 are similar fragmental sectional elevations, taken on the line 5—6 of Fig. 3; Fig. 5 indicating the slide valve in closed position, and Fig. 6 indicating the valve in substantially fully opened position.

The drawings show a preferred embodiment of my improved carburetor, indicated as a "down draft" type, though my invention is not to be considered as limited to this type.

In the drawings, 1 indicates an air-inlet conduit, shown as mounted in vertical alignment with a mixture-delivery conduit 2, and separated from the latter by an interposed partition block or casing 3. The conduit 2 is shown as flanged at 4 for connecting, either directly or through an interposed tube, with the inlet manifold of the engine, not shown. And casing 3 is shown with vertical apertures later more fully described, forming air passage-ways connecting the conduits 1 and 2; and with a recessed seat 5 in which is fitted a slide valve 6 projecting through an open end in said casing and retained in said recess by a front

face cover plate 7. The valve 6, as later herein described, is arranged to slide across and close certain of the vertical air passageways connecting tubes 1 and 2, and is operated, as shown, by a vertically swinging arm 8, extending through a slotted opening 9 in the top wall of casing 3; the lower end of said arm 8 being pivoted at 10 in an opening 11 of valve 6, and its upper end having a slot 12 pivotally engaging a pin 13 on a standard 14, mounted on casing 3. A bell crank lever is shown as having its axle portion 15 mounted in a suitable bearing 16 carried by casing 3, with one end 17 of said lever pivotally engaging in a slot 18 in arm 8, and its other end 19 adapted for connection with a usual throttle lever, or other means not shown, for controlling the engine speed in known manner. This means for operating slide valve 6, it will be noted, provides for a cam-like action, due to the bell-crank engagement with swinging arm 8, and producing a desired slow initial opening movement of the valve with increase of its speed as it is opened wider, and reversely a quick initial closing movement with reduced speed as it approaches its fully closed position, thus permitting nicety of adjustment in the partial openings with quicker response for increased demands.

The slide valve 6, above described, is arranged to move transversely to open or close air passageways in partition casing 3, such openings, as shown in the drawings, being preferably divided by a separating wall 25 into a substantial rectangular opening 26, and a substantially triangular opening 27, a third round opening 28 beyond the traverse of valve 6 being provided for idling speeds as later herein more fully described. The valve 6 progressively moves to open and close these air passageways, and it will be noted, the triangular passageway provides for greatly reduced air passages as the valve approaches its extreme inward movements. To continue this division of air passing through apertures 26 and 27, conduit 1, as shown, is provided with a partition wall 30, registering with the separating wall 25 and extending upwardly therefrom to divide conduit 1 into two vertical portions for a portion of its height.

The liquid fuel is delivered from a suitable source of storage, through a pipe 35 to a float valve chamber 36, which may be of any usual construction adapted to maintain a controlled delivery through a tube 37 to a tubular passage-way 38, formed in and extending inwardly from one end of block 3 to an interior point beyond the air passageway 26. This passage-way, 38

forms a common or main fuel inlet for a plurality of vertical branches 39, and 40, shown as spaced along the length thereof and each branch having a right-angled extension, such extension 41 from branches 39 opening into air passageway 26, and such extensions 42 from branches 40 opening into air passageway 27. The passageways for the fuel are alone shown in the drawings, but they may be readily formed by drilling meeting holes of proper diameter inward through the outer walls and plugging the unused portions thereof in any convenient manner. The open ends of the branch extensions 41 and 42 are preferably provided with outlet nozzles or jets 43 and 44 screwed into the air passage way wall and extending into the latter an effective distance to deliver their liquid fuel in the form of an atomized spray as called for by the air passing over them. Further these spray nozzles 43 and 44 extend outwardly from the walls of air passageways 26 and 27, above, or on the air inlet side of slide valve 6, so that when the latter closes said passageways, no suction induced by the engine cylinder can act to draw fuel from them, but when the valve is moved to open said passageways, these jets will act to supply fuel to the passing air in accordance with the flow call of the latter.

As before stated casing block 3 has a third aperture 28 forming an air passageway between conduits 1 and 2 for a combustible fuel mixture suitable for idling speeds of the engine, and not affected by the slide valve 6, so as to maintain such feed when the slide valve entirely closes passageways 26 and 27. This passageway is shown as having an angular extension 50 from a fuel supply branch 51 from main fuel passageway 38, and a nozzle 53 in aperture 28. Conduit 1 is shown with a thickened wall portion 54 having an aperture 55 in register with aperture 28 and forming an air inlet thereto. 56 indicates a screw bolt valve extending through the wall of conduit 1 into said aperture 55 to control the air inlet opening thereof, and 57 indicates a screw bolt valve extending into and controlling the discharge opening of aperture 28 below nozzle 53. These two valves are adjustable to set position to regulate the proper supply of combustible mixture to insure idling operation of the motor without danger of its stopping for lack of fuel.

The air inlet conduit 1 is shown as having a butterfly valve 60 controlling the air admission thereto, particularly useful in starting, as swung by the usual choke lever mechanism to provide a rich starting mixture. Its later use is generally unnecessary, and it may be set, after starting, to fully opened position for admission of air to conduit 1, and the movement of slide valve 6, progressively opening air passageways 27 and 26 provides all necessary control of the fuel mixture determined by the suction free of such air passing over fuel nozzle 43 and 44, as they progressively come into such air flow by the movement of valve 6, to insure adequate supply of fuel for the mixture.

In some cases, for extra power and speed, special enrichment of the combustible mixture may be desired, and this is provided for as shown in the drawings by an added spray nozzle 70, extending laterally from a stud post 71 projecting upwardly from block 3 in air conduit 1. This post has an interior extension 72 to a branch 73 connecting with main fuel supply passageway 38. Such additional spray nozzle is not necessarily limited to one, as two or more may be employed, and the

nozzle may desirably have a larger diameter spray opening than nozzles 43 and 44, for increased discharge therefrom.

An important feature to note is that fuel nozzles 43, 44 and 53 are in a horizontal alinement, and float valve chamber 36 is so positioned as to maintain a fuel level in main passageway 38 and its plurality of vertical branches well below the respective nozzles for the latter, so that flow through said nozzles will occur only when the suction of the motor induces air flow across them. Another feature to note is that nozzle 70, or an other like added nozzle, is shown at a higher level than nozzles 43, 44 and 53, so that flow therefrom occurs only in the higher vacuum suctions of the motor. The alinement of nozzles 43, 44 and 53, may of course be stepped as to height, if desired, to cause feedings at varying suctions, if desired.

Another feature to note particularly, is that slide valve 6 is "self sealing," that is, it is drawn to its seat by vacuum suction of the motor when operating, so that inaccuracies or looseness of fit of said slide, does not affect its operation. And moreover, movement of said slide valve 6, when the motor is idle, can have no pumping action or suction to draw fuel from the feed nozzles, as such drawing of fuel and mixture with air is determined and regulated solely by the suction action of the motor in operation, thus insuring a proper regulation of such mixture for effective and economical operation of the motor.

The starting of the motor, in most cases, will require only a partial opening of slide valve 6 to uncover a portion of air passageway 27, the turning over of the motor drawing in air through conduit 1 and over one or more nozzles 44 to furnish such air with fuel drawn from such nozzles by the passing air. When a richer starting mixture is desired, as starting in cold weather, butterfly valve 60 is closed to choke or shut off the admission of air to conduit 1, thus increasing the vacuum suction in such conduits, so that fuel may be drawn from all the nozzles if necessary, regardless of the position of slide valve 6, merely uncovering a portion of passageway 27. When the valve 60 is thus closed, fuel in the form of spray will be drawn upwardly from nozzles 43, and 70 when employed, to rise over partition wall 30 and then descend to pass through passageway 27, producing a rich and very thoroughly mixed charge, reduced as soon as the engine is properly running by opening valve 60, so the charges may be governed by slide valve 6 for ordinary running operation of the motor.

For idling operation of the motor, passageway 28 will suffice to furnish a sufficiency of proper combustible mixture, such idling feed being adjustably set by operation of screw bolt valves 56 and 57.

For starting, with the valve 60 closed as above described, fuel from all the nozzles may feed to enrich the mixture, though under general conditions use of valve 60 is not necessary, as sufficient richness is furnished by the air passing through the partially opened passageway 27.

For ordinary motor operation, movement of slide valve 6, progressively uncovering passageways 27 and 26, and reversely closing them, will produce adequate and economical combustible mixtures for all normal speeds.

And for higher speeds and increased loads, additional fuel to enrich the mixture may be supplied by the higher positioned nozzle or nozzles

10 as described, the height thereof determining the suction required to draw fuel therefrom.

In connection with the above, a very important feature to be noted is, that by separating passageway apertures 21 and 25 by partition wall 25 and conduit 1 divided by partition 30, practically dual air flow passageways 21 and 25 are provided, which, as progressively opened by slide valve 6, produce a dual carburetor action. Passageway 21 forms a limited flow initial carburetor, and passageway 25 an added increased speed and power carburetor, and when both are shut off passageway 28 provides mixture for maintained idling of the engine. This dual action provides for desirable economical operation for general use, with immediate increased power when required for heavier loads or higher speeds, all combined in one carburetor and controlled by a single slide valve.

In all such feeding, the fuel supplied is determined solely by the vacuum call of the motor, which can and will draw just the proper amount of fuel necessary for proper combustion, thus ensuring economical operation at all speeds.

From the foregoing description it is believed the nature of my improvements and the manner of operation will be clearly understood,—the feed nozzles supply fuel as called for by the engine vacuum under control of the slide valve, with a fixed idling feed through passageway 28, and an excess fuel supply through nozzle 70; said slide valve being self sealing to prevent fuel feed except as controlled, and having a variable traverse for quicker opening for higher demands and slower movements when in the more nearly closed position.

The particular embodiment shown in the drawings and above specifically described may of course be modified within the scope of the invention as defined in the following claims.

What I claim is:

1. In a carburetor for internal combustion engines, an air inlet conduit, a mixture delivery conduit, and a transverse intermediate member between said conduits having a fuel-mixing aperture with straight sides alined with said conduits and forming a straight air passageway through the latter, a row of fuel spray nozzles extending laterally into said mixing aperture and brought

into operation by suction of air passing over them, a partition wall in said mixture delivery conduit, another partition extending into said fuel-mixing aperture in said intermediate member beyond said row of fuel spray nozzles, such other partition being a continuation of said first named partition wall and dividing the fuel mixing aperture in said intermediate member into two passageways, one of which is triangular in cross-section, a slide valve mounted in said intermediate member in spaced relation between said spray nozzles and said delivery conduit, actuating mechanism for sliding said valve to vary the opening of said aperture and the number of spray nozzles brought into operation, and a separate spaced fuel-mixing passageway forming a constantly open air passageway connecting said conduits.

2. In a carburetor for internal combustion engines, an air inlet conduit, a mixture delivery conduit, and a transverse intermediate member between said conduits having a fuel-mixing aperture with straight sides alined with said conduits and forming a straight air passageway through the latter, a row of fuel spray nozzles extending laterally into said mixing aperture and brought into operation by suction of air passing over them, a partition wall in said mixture delivery conduit, another partition extending into said fuel-mixing aperture in said intermediate member beyond said row of fuel spray nozzles, such other partition being a continuation of said first named partition wall and dividing the fuel mixing aperture in said intermediate member into two passageways, one of which is triangular in cross-section, a slide valve mounted in said intermediate member in spaced relation between said spray nozzles and said delivery conduit, actuating mechanism for sliding said valve to vary the opening of said aperture and the number of spray nozzles brought into operation, and a separate spaced fuel-mixing passageway forming a constantly open air passageway connecting said conduits, the fuel mixing aperture of triangular cross-section, in said intermediate member, being located in such manner that the opening converges as said valve closes.

HAROLD D. REGAR.
